COMBINED TOY BANK AND CANDY CONTAINER
OR SIMILAR ARTICLE

Otto J. Glaser, Philadelphia, Pa., assignor to James Candy
Company, Atlantic City, N. J., a corporation of New
Jersey

Application May 13, 1954, Serial No. 30,469

Term of patent 14 years

(Cl. D34—11)

FIG. 1.

FIG. 2.

To all whom it may concern:

Be it known that I, Otto J. Glaser, a citizen of the United States, residing at Philadelphia, Pennsylvania, have invented a new, original, and ornamental Design for a Combined Toy Bank and Candy Container or Similar Article, of which the following is a specification, reference being had to the accompanying drawing, forming a part thereof and wherein:

Figure 1 is a top plan view of a combined toy bank and candy container or similar article, showing my new design; and

Figure 2 is a side elevational view thereof.

The dominant features of my new design are shown in solid lines in the drawing.

I claim:

The ornamental design for a combined toy bank and

candy container or similar article, substantially as shown and described.
